(57)

CLAIM

The ornamental design for a baby bed as shown and described.

DESCRIPTION

1.1: Perspective

1.2: Perspective

1.3: Perspective

1.4: Front

1.5: Top

1.6: Side

1.7: Bottom

Baby bed with star-shaped frame structure that forms the frame itself including the legs of the baby bed; a cocoon is stretched inside the frame structure, forming the lying surface and a nest like border.

1 Claim, 7 Drawing Sheets
